UNITED STATES PATENT OFFICE.

WILLIAM F. ANKLAM, OF DETROIT, MICHIGAN, ASSIGNOR TO C. M. HALL LAMP COMPANY, OF DETROIT, MICHIGAN, A CORPORATION OF MICHIGAN.

LAMP-SOCKET.

1,082,484.

Specification of Letters Patent. Patented Dec. 30, 1913.

Application filed May 26, 1913. Serial No. 769,927.

To all whom it may concern:

Be it known that I, WILLIAM F. ANKLAM, a citizen of the United States of America, residing at Detroit, in the county of Wayne 5 and State of Michigan, have invented certain new and useful Improvements in Lamp-Sockets, of which the following is a specification, reference being had therein to the accompanying drawings.

10 My invention relates to lamp sockets and resides in the novel construction of the socket whereby the illuminant may be easily and accurately focused in relation to the reflector; in a construction in which twisting 15 of the wires or leads that are operatively connected to the plug will be eliminated; in means for retaining the socket parts in their adjusted position; and in certain arrangements and constructions of parts as will 20 more fully hereinafter appear.

In the drawings,—Figure 1 is a fragmentary section through a lamp having my improved socket applied thereto; and Fig. 2 is an enlarged, central, longitudinal section through the plug.

A designates the outer casing of the lamp, and B the reflector therein, herein shown as parabolic form. C is the lamp globe or illuminant, arranged within the reflector. 30 It is very desirable—in order to obtain the best efficiency of the illuminant—that the latter is in proper focus in relation to the reflector; and as the filaments in lamp globes of the same size vary as to their focal point, 35 it is necessary to have the socket for the lamp globe or other illuminant so constructed that it may be moved into proper focus with the reflector. In the present construction this is accomplished by providing a 40 relative, rotary movement between the socket parts. In the structure shown in the drawings the lamp bulb C is carried by a plug D which has a screw-threaded engagement with a mounting or bearing portion 45 of the socket, suitably attached to a support. Preferably this mounting comprises a sleeve E attached to and carried by the reflector and having an opening therein alining with an opening in the base of the reflector. 50 Thus the plug may be adjusted to vary the position of the illuminant by merely turn-

ing the plug, and the turning of the latter may be accomplished by revolving the globe C. In order to permit of this turning action without damage to the electrical leads 55 F G, I have devised a novel construction of socket which will allow of the turning of the plug within the sleeve any number of revolutions. Thus, H is an insulating core or body which is provided with bores I J 60 extending longitudinally thereof. Arranged within these bores are the terminals, which are preferably of the spring-pressed type and may be of any suitable construction. Surrounding the core is a metallic sleeve K 65 which is secured to the core H and also electrically connected to one of the terminals as L through the medium of a pin M. N is a second metallic sleeve spaced from the sleeve K by means of an insulating ring O. 70 The sleeve N is attached to the other terminal P in a manner similar to that described in connection with the sleeve K, and this sleeve N is also insulated from the socket portion Q which receives the lamp globe, 75 by a ring R of insulating material.

The member Q has an inwardly-extending flange S upon which is seated the head T of the core H. In assembling the parts the core is inserted through the member Q 80 until the head T thereof engages its seat S, and when the sleeves N K are secured in place by the pins M the several parts are rigidly connected together against longitudinal displacement. In order to prevent 85 relative rotation between the portion Q and the core H the latter is preferably secured to the former by means of a pin U.

The sleeve E within which the plug is arranged, is provided with sockets V W 90 slightly spaced and internally threaded to receive the threaded ends X of insulating members Y which carry the terminals Z that are electrically connected to the wires F G that lead to the source of electrical current. The members Z are spring-pressed and when the parts are as shown in Fig. 1 the outer ends of the members Z are yieldably pressed in engagement respectively with the sleeves K N, thereby establishing 95 100 electrical connection between one of the members Z and the terminal P through the

medium of the pin M and the sleeve N, and between the other members Z and the terminal L through the medium of the pin M and sleeve K. The sleeves K N are of sufficient width to permit of the necessary longitudinal adjustment of the plug during the adjustment of the members E in effect forming brushes that during all positions of adjustment remain in contact with their respective sleeves. Furthermore, when the plug has been moved to an adjusted position, the action of the springs upon the members Z will exert a sufficient pressure upon the plug to avoid accidental rotation of the latter, due to jarring or the like.

While I have shown and described a desirable form of my invention it is readily apparent that the same is susceptible of various modifications, and I do not desire to limit my protection to the structure shown, but consider the invention sufficiently broad to embody various modifications thereof.

What I claim as my invention is:—

1. In a lamp socket, the combination of a plug comprising a lamp-receiving socket portion, terminals arranged in said socket portion, an insulating core carrying said terminals, spaced metallic bands upon said core, insulating material interposed between the adjacent ends of said bands, means for electrically connecting each of said bands with one of the terminals, a sleeve within which said plug is arranged for longitudinal and rotary adjustment, contact sockets on said sleeve, and spring-pressed contacts in said sockets respectively engaging said metallic bands.

2. The combination of a reflector of a lamp, a plug having a lamp-receiving socket portion formed as a unit therewith, a terminal carried by the plug extending into the socket portion, a bearing for the plug arranged to position the lamp-receiving socket in operative relation to the reflector, a screw-threaded engagement between the bearing and the plug for permitting the adjustment of the socket portion relative to the reflector, and means for holding the plug and bearing in any position of relative adjustment.

3. The combination of a reflector of a lamp, a plug having a lamp-receiving socket portion formed as a unit therewith, a terminal carried by the plug arranged to position the lamp-receiving socket in operative relation to the reflector, a screw-threaded engagement between the bearing and the plug for permitting the adjustment of the socket portion relative to the reflector, and yielding means for releasably holding the plug and bearing against relative movement.

4. The combination of a reflector of a lamp, a plug member having a lamp-receiving socket portion, a terminal carried by the plug and projecting into the socket portion, a bearing for the plug arranged to position

the lamp-bulb engaging portion in operative relation to the reflector, an engagement between the bearing and plug for effecting upon a relative rotation of the plug and bearing a longitudinal adjustment of the plug relative to the reflector, a contact carried by one of said members and having a frictional engagement with the other member and acting to retain the plug and bearing members in different positions of relative adjustment, and means for electrically connecting said terminal and contact.

5. The combination of a reflector of a lamp, a plug member having a lamp-receiving socket portion, a terminal carried by the plug and projecting into the socket portion, a bearing for the plug arranged to position the lamp-bulb engaging portion in operative relation to the reflector, an engagement between the bearing and plug for effecting upon a relative rotation of the plug and bearing a longitudinal adjustment of the plug relative to the reflector, a contact carried by one of said members yieldably pressed into engagement with the other member and acting to yieldably retain the plug and bearing members against relative adjustment, and means for electrically connecting said terminal and contact.

6. The combination of a reflector of a lamp, a plug member having a lamp-receiving socket portion, a terminal carried by the plug and arranged in operative relation to the socket portion, a bearing member for the plug arranged to position the lamp-bulb engaging portion in operative relation to the reflector, a connection between the plug and the bearing for effecting upon a relative rotation a longitudinal movement of the plug relative to the reflector, a conducting surface on one of said members electrically connected to said terminal, and a contact on the other of said members in electrical engagement with said conducting surface in various positions of relative adjustment of said members, the engagement between the contact and conducting surfaces serving to retain the plug and bearing in their positions of adjustment.

7. The combination of a reflector of a lamp, a plug member having a lamp-receiving socket portion, a terminal carried by the plug and arranged in operative relation to the socket portion, a bearing member for the plug arranged to position the lamp-bulb engaging portion in operative relation to the reflector, a connection between the plug and the bearing for effecting upon a relative rotation a longitudinal movement of the plug relative to the reflector, a conducting surface on one of said members electrically connected to said terminal, and a spring-pressed contact on the other of said members yieldably engaging said conducting surface in various positions of relative adjustment.

adjustment of said members and acting to yieldably retain the plug and bearing in their various positions of adjustment.

8. The combination of a reflector of a lamp, a plug member having a lamp-receiving socket portion, a terminal carried by the plug and arranged in operative relation to the socket portion, a bearing member for the plug arranged to position the lamp-bulb engaging portion in operative relation to the reflector, a connection between the plug and the bearing for effecting upon a relative rotation a longitudinal movement of the plug relative to the reflector, an endless conducting surface on one of said members, an electrical connection between said surface and the terminal, and a spring-pressed contact carried by the other of said members and engaging said endless conducting surface.

9. The combination of a reflector of a lamp, a plug having a lamp-receiving socket portion, a terminal carried by the plug and projecting into the socket, a bearing for the plug arranged to position the lamp-bulb engaging portion in operative relation to the reflector, an engagement between the plug and the bearing for effecting upon a relative rotation a longitudinal adjustment of the plug relative to the reflector, an endless metallic surface on the plug electrically connected to the terminal, and a spring-pressed contact carried by the bearing and yieldably engaging said endless surface in various positions of adjustment of the plug and bearing.

10. The combination of a reflector of a lamp, a plug having a lamp-receiving socket portion, a terminal carried by the plug and projecting into the socket, a bearing for the plug, comprising a stationary sleeve arranged to position the lamp-bulb engaging portion in operative relation to the reflector, a connection between the plug and sleeve for effecting upon a relative rotation a longitudinal adjustment of the plug relative to the reflector, an endless metallic surface on the plug electrically connected to said terminal, and a spring-pressed contact carried by the sleeve and fixed in relation thereto, said contact yieldably engaging the endless metallic surface of the plug in various positions of adjustment of the plug and sleeve and acting to releasably retain the socket and sleeve against relative rotation.

11. The combination of a reflector of a lamp, a plug having a lamp-receiving socket portion, a terminal carried by the plug and projecting into the socket, a bearing for the plug, comprising a stationary sleeve arranged to position the lamp-bulb engaging portion in operative relation to the reflector, a connection between the plug and sleeve for effecting upon a relative rotation a lon-

itudinal adjustment of the plug relative to the reflector, an endless metallic band encircling the plug and electrically connected to said terminal, and a spring-pressed contact carried by the sleeve projecting laterally therethrough into engagement with the metallic band whereby an electrical connection is established between said terminal and said contact in various positions of adjustment of the plug and sleeve.

12. The combination of a reflector of a lamp, a plug having a lamp-receiving socket portion, a pair of terminals carried by the plug and projecting into the socket portion, a pair of endless metallic surfaces on the plug insulated the one from the other, means for electrically connecting said surfaces respectively with said terminals, a sleeve within which said plug is positioned, said sleeve being arranged to position the lamp-bulb engaging portion in operative relation to the reflector, an engagement between the plug and sleeve for effecting upon a relative rotation a longitudinal adjustment of the plug relative to the reflector, and a pair of terminals carried by said sleeve and respectively engaging said endless metallic surfaces.

13. The combination of a reflector of a lamp, a plug member having a lamp-receiving socket portion, a terminal carried by the plug and projecting into operative relation to the socket portion, a bearing with which said plug is engaged arranged to position the socket portion in operative relation to the reflector, a connection between the bearing and plug for effecting a longitudinal adjustment of the socket portion relative to the reflector, a contact carried by and fixed in relation to the bearing, and means for maintaining an electrical connection between the terminal and contact in various positions of adjustment of the plug and bearing.

14. The combination of a reflector of a lamp, a plug having a lamp-receiving socket portion, a terminal carried by the plug and positioned in operative relation to the socket portion, a bearing for the plug non-rotatably mounted and arranged to position the lamp-bulb engaging portion in operative relation to the reflector, a connection between the plug and bearing for effecting a longitudinal adjustment of the plug relative to the bearing, a contact fixed in relation to the bearing, and means carried by the plug for electrically connecting said contact and said terminal.

15. The combination of a reflector of a lamp, a plug having a lamp-receiving socket portion, a terminal carried by the plug and projecting into the socket portion, a sleeve carried by and fixed in relation to the reflector and within which said plug is arranged, a connection between said sleeve and

and plug for effecting upon a rotation of the plug a longitudinal adjustment of the socket portion relative to the reflector, a contact carried by the sleeve and means for
5 maintaining an electrical connection between said terminal and said contact in the various positions of adjustment of said plug.

In testimony whereof I affix my signature in presence of two witnesses.
